UNITED STATES PATENT OFFICE.

GEORG KIRKEGAARD, OF NEW YORK, N. Y.

HEAD FOR BOTTLE-CAPPING MACHINES.

No. 873,245.

Specification of Letters Patent.

Patented Dec. 10, 1907.

Application filed October 1, 1906, Serial No. 336,831.

To all whom it may concern:

Be it known that I, GEORG KIRKEGAARD, a citizen of the United States, and a resident of the city of New York, in the county of New York and State of New York, United States of America, have invented certain new and useful Improvements in Heads for Bottle-Capping Machines, of which the following is a specification.

10 My invention relates to heads for bottle capping machines and its object is to provide a simple device which will be more efficient than those now in use.

I will describe my invention in the following specification and point out the novel features thereof in claims.

Referring to the drawings, Figure 1 is a side elevation of a head for a bottle capping machine made according to my invention. 20 Fig. 2 is a sectional side elevation of the same device. Fig. 3 is a plan view and Fig. 4 is an inverted plan view of the device shown in Figs. 1 and 2. Figs. 5 and 6 are, respectively, a side elevation and a plan view of a bottle stopper which I have invented and which is fully described in Letters Patent No. 829,341, issued to me under date of August 21st, 1906.

Like characters of reference designate corresponding parts in all of the figures.

10 designates a head or die for a machine used for applying bottle stoppers to bottles. This head comprises three parts 20, 30 and 40 which are substantially alike. These 30 three parts are sectors of a circular body so that when they are placed together they form a circular head or die. The outer surfaces of this die may be provided with a series of parallel grooves 31. A spring 32 is 40 arranged to be placed in one of these grooves, or a plurality of such springs may be used if desired. All these springs are preferably constructed of spring steel or brass wire of circular cross-section and are in the form 50 of a circular ring split at 33, the inner diameter of which is somewhat less than that of the bottom of the grooves 31. When placed upon a head these springs not only hold the three sectors of the head together but also 60 serve the purpose of holding them in horizontal alignment. I sometimes provide springs made of different sizes of wire for use in conjunction with this head in order to vary the tension under which these parts are held 70 together and can use one or more of such

springs according to the work to which the head is to be applied.

The inner surface of the head is provided with cam shaped grooves such as 35. This groove has a cross-sectional shape designed to fit over lugs and projections on the bottle cap or stopper with which it is designed to be used and which will be described herein-after. Each of the grooves is vertically inclined so that its distance from the central axis of the head is greater at the bottom of the head than it is at the top of the head. I prefer to make the lower part 36 of this incline at a greater angle from the vertical than is the upper portion 37. Each of the three sectors is provided with a groove similar to that which is described. The inside diameter of the head is of sufficient size to allow the head to pass over the bottle stopper with which it is to be used.

75 A pin 34 is shown in one of the sectors. This pin may be provided for the purpose of preventing the head from rotating in the press or other machine in which it is used.

At 50, in Figs. 5 and 6, is shown a bottle stopper which I have invented and which I will now briefly describe. It comprises a disk portion 51 having an annular depending flange 52 integral with which are two fingers 53, 53 of sufficient length to engage with the neck of a bottle to which it is to be applied, and a third finger 54 similar to the others but considerably longer. These fingers are provided as shown, for example at 55, with projecting ribs for the purpose of stiffening and strengthening the bottle cap structure. In applying these caps or stoppers to the neck of a bottle a packing is first placed within the disk portion of the cap which is then placed upon the neck of a bottle with the three fingers slightly spread apart. The lower portion of the head 10 is then placed over the cap 50. This head is especially designed for the cap above described in this case and the cam-shaped grooves are arranged to fit over the fingers 53 and 54. The shape of the grooves is such that they will not crush the projecting ribs such as 55 and the indentations 38 are provided for this purpose. The head is then pressed down over the cap 100 and the neck of the bottle by any suitable means. A steep incline of the lower part of the grooves, such as 36, will cause the first part of this movement to press the three fingers of the cap quickly inward against the 110

bottle, when the upper part, such as 37, of the grooves will come in contact with the fingers. A further downward movement of the head under pressure will cause the fingers to 5 be pushed in against the bottle with great force causing the cap, because of the peculiar construction of its fingers and the shape of the neck of the bottle, to be firmly locked to the bottle. Heretofore, heads similar in 10 shape to the one herein shown and described have been used for this purpose. It has been found that when such heads are used, if the pressure upon the heads is too great, or if the head is pushed down too far, or if a bottle 15 with a neck slightly larger than others is used the neck will be crushed and the bottle destroyed, unless means are provided for rendering them yieldable. In the present invention this difficulty is overcome for, as 20 soon as the pressure becomes excessive for any cause, the head itself will expand against the action of the spring or springs 32 which may be as heavy or as light as desired. These heads greatly facilitate the operation 25 of applying caps to the necks of bottles as the operation may be made with greater certainty and at a much higher rate of speed and entirely without the costly breakage caused by the solid heads heretofore used.

30 In illustrating my invention I have shown a bottle stopper which I have invented and a head for capping machines which is designed to be used with this particular stopper. It is obvious that the principle of this invention 35 may be embodied in other forms of bottle capping heads and that the heads may be designed to be used in conjunction with other bottle stoppers of this class.

What I claim is.—

- 40 1. A plurality of sectors together forming a hollow circular die, the inner surface of said die being arranged to coact with parts of a bottle stopper cap, a horizontal groove on the outer surfaces of said sectors, and a spring 45 in said groove arranged to hold said sectors together.
2. A plurality of sectors together forming a hollow circular die, the inner surfaces of said die being arranged to coact with parts of

a bottle stopper cap, horizontal grooves on the outer surfaces of said sectors, and split rings in said horizontal grooves arranged to yieldably hold said sectors together. 50

3. A plurality of sectors, together forming a hollow circular die, said die being arranged 55 to be used in conjunction with a bottle stopper cap, horizontal grooves on the outer surfaces of said sectors, a cam-shaped groove on the inner surface of each of said sectors, said grooves being arranged to coact with parts 60 of said cap, and springs in the horizontal grooves arranged to yieldably hold said sectors together and to hold the sectors in horizontal alinement.

4. A plurality of sectors, together forming 65 a hollow circular die, said die being arranged to be used in conjunction with a bottle stopper cap, horizontal grooves on the outer surfaces of said sectors, a cam-shaped groove on the inner surface of each of said sectors, said 70 grooves being arranged to coact with parts of said cap, and provided with indentations for clearing other parts of the cap, and springs in the horizontal grooves arranged to yieldably hold said sectors together and to hold the 75 sectors in horizontal alinement.

5. A plurality of sectors together forming a hollow circular die, said die being arranged 80 to be used in conjunction with a bottle stopper cap, horizontal grooves on the outer surfaces of said sectors, a cam-shaped groove on the inner surface of each of said sectors, said 85 grooves having two parts at different angles from the axis of the die and arranged to coact with parts of said cap, and being provided with indentations for clearing other parts of the cap, and split rings in the horizontal grooves arranged to yieldably hold said sectors together and to hold the sectors in horizontal alinement. 90

In testimony whereof I have signed my name to this specification in the presence of two subscribing witnesses.

GEORG KIRKEGAARD.
